CIGARETTE CHUTE

Louise E. Harris, Macon, Ga.

Application July 18, 1949, Serial No. 105,299

1 Claim. (Cl. 232—43.1)

1

This invention relates to public sanitation and more particularly to the disposition of cigar and cigarette butts which are discarded after the smoker has finished with them. Specifically, the invention is directed to structure for receiving and retaining cigar and cigarette fragments and the ashes produced from the burning of the same.

Various types of receptacles for cigar and cigarette butts have been provided in the past, some of which include open top relatively heavy receptacles containing sand, water or the like so that the fire of a burning cigarette or cigar may be thrust into the same thus extinguishing the fire. Other prior devices of this character have been constructed to operate on the exclusion of air to produce the same result, while still further devices are merely trays. Where there is substantial volume of discarded cigar and cigarette butts the immediate area usually becomes unsightly regardless of the type of receptacle that has been provided and the odor is ordinarily offensive or obnoxious.

It is an object of the invention to provide improved receiving structure the use of which will be more satisfactory from the viewpoint of efficiency, convenience, sanitation, and appearance.

Another object of the invention is to provide cigar and cigarette disposal means which can be inexpensively produced of any desired size and capacity, which is relatively simple and can be easily installed, which is artistic in appearance, which will discourage carelessness in the disposition of cigar and cigarette butts, burnt matches and the like, thereby eliminating unsightly and costly burns on rugs, floors, carpets and furniture as well as reducing the fire hazard and more nearly satisfying the underwriters and thus reducing the cost of insurance.

Another object of the invention is to provide disposal means which can be self-contained, used on a single floor of a building or which may consist of a plurality of disposal chutes having receiving openings on a plurality of different floors of a building or buildings.

The invention particularly contemplates disposal structure designed to fit into surroundings where it is used without detracting from, but preferably contributing to the artistic or aesthetic, and which will contribute toward the education of the general public in sanitation, respect for the property of others, and good personal habits of neatness and general social behavior.

Further objects and advantages of the invention will be apparent from the following descrip-

2

tion taken in conjunction with the accompanying drawings, wherein:

Fig. 1 is a diagrammatic view illustrating the present invention;

5 Fig. 2, an enlarged fragmentary detail, partly broken away, of a portion of the discharge unit of Fig. 1;

Fig. 3, a further detail of the separating and aerating unit;

10 Fig. 4, a view similar to Fig. 1, illustrating a modified form of the present invention;

Fig. 5, a vertical section on the line 5—5 of Fig. 4;

15 Fig. 6, a section on the line 6—6 of Fig. 5; and,

Fig. 7, a top plan view of the device shown in Figs. 4, 5, 6.

With continued reference to the drawings, and more particularly to Figs. 1—3, inclusive, for purposes of illustration, the present invention contemplates among other things a continuous vertical housing or chute structure 10, having fastening flanges 10' and extending from the basement to the uppermost floor of a building, which flanges may be secured to the walls thereof.

The said chute may be disposed conveniently to the doors 11, of an elevator system close by the elevator call buttons 12, it being understood that smokers when in this location usually discard their cigarettes or cigar ash or stubs, the fumes of which are sometimes particularly offensive or obnoxious in a closed elevator.

Provision is made for the introduction of cigarette or cigar ashes or butts on each floor 35 13, of a building, in which the device of the present invention is installed, by providing an enlarged portion 14 in the chute 10, which may be made to attractively match the immediate surroundings thereof.

40 The enlarged portion 14 has a gently curved deflecting surface 15, on its lower extremity, at the point where such portion contacts the floor 13. The top of the enlarged portion 14 is provided with an opening 16, about which a guard rail 17 is displaced, to retain articles to be received by said chute.

45 A match striking plate 18 extends from one side wall to the other side wall of said opening 16, and is angularly positioned to direct articles thrown in contact therewith toward and into the main body of the enlarged portion 14. Similarly, a grill 19, having open work 20, is positioned at the opposite side of the opening 16, in the enlarged portion 14, nearest the chute 10, which will 55 afford the user a very satisfactory means of

knocking the ashes out of his pipe, it being understood that in the event the pipe should be released by the user, it will not be lost in the device, as the grill 19, will prevent it from falling into the opening and thence down the length of the chute 10. The grill 19 also provides a very satisfactory place to "grind out" cigarette butts, in the event the user should desire to do so. The open work 20, in the grill 19, allows ashes from pipes, or butts to pass therethrough, thence into the chute 10.

A relatively narrow slot 21 is also provided in the opening 16 of the enlarged portion 14, as defined by the innermost edges of the match striking plate 18, and the grill 19, such provision being made to directly receive ashes, butts, or matches, when the user does not desire to "grind out" or otherwise extinguish the same.

It will thus be readily seen that when a butt or other article to be disposed of enters the opening 16 either through the slot 21 or the open work 20 of the grill 19, it will travel downwardly through the enlarged portion 14, until said butt or article to be disposed of strikes the curved deflecting surface 15 contained therein where said butts or other articles to be disposed of will be positively directed to the chute 10, for disposal thereof.

The end or lowermost portion of the chute 10, is directly connected to a conically shaped receiving member 22, thence to a relatively powerful air pump 23 which continuously draws air through the chute 10, and the enlarged portions 14 attached thereon, which action discourages the adherence of butts, ashes or other matter, to the inside walls of the chute 10 and the enlarged receiving portions 14, thus affording a positively clean chute and entry means, it being noted that there are no ledges or other causes for articles to be disposed of to collect on, thereby providing a sanitary unit free from dust or offensive odors.

Air, drawn by the air pump 23, through the connecting member 22, from the chute 10 and its entry means, will necessarily contain articles to be disposed of, therefore a cyclone separator 24 may be provided for receiving the said air and contents thereof by means of a connecting tube 25, said tube being attached to the discharge end of the air pump 23, thence to a point midway, and off center of the widest portion 26 of the said separator 24.

The contaminated and refuse carrying air will enter the separator 24 under a relatively high pressure due to the action of the pump 23 and will circulate therein at a high rate of speed in its widest portion 26, until the refuse, because of gravity gently detaching it from the highly rotating air stream will gradually pass downwardly to the narrow portion 27 of the said separator, where the air stream becomes less violent progressively downward until such refuse will be received in a discharge tube 28 attached to the lowermost portion of said separator. The air will thus be aerated as well as have particles removed therefrom.

A suitable refuse collection box 29 is located directly beneath the discharge tube 28, for retaining articles to be disposed of, and in which such articles will gently come to rest because of the holding action of the turbulent air within the separator 24, thus causing little or no dust to rise and said articles will settle therein. The uppermost portion of said separator may be provided with a relatively short narrow neck opening 30, for the discharge of air, and is equipped with a screen or other filtering means 31 to

separate any particles which may attempt to pass therethrough.

A convex baffle plate 32 supported by legs 33 is provided to support the same in spaced relation to the air discharge opening 30, thus disbursing the now filtered air evenly through the basement or other part of the building in which the same may be installed. A framework 34, supported by legs 35, mounted on a basement or other floor 36, forms the supporting means for the said separator.

It should also be understood that the present invention is not limited to the separator shown in the drawings, as the receiving tube 22 could readily be attached to an incinerator or furnace, not shown, or the articles to be disposed of could be carried away by conveyors to an appropriate or otherwise desirable location within the building.

A modification of the above described device is more clearly illustrated in Figs. 4-7, inc., wherein an individual receptacle 37 may be placed on each floor of the building without the use of a general collection chute, when circumstance will not permit; or for placing the same throughout the various parts of a structure without the necessity of aligning the same for unitary disposal thereof.

The receptacle 37 is provided with a pair of flanges 38, by means of which said receptacle may be secured by bolts or other fastening elements 39, to a wall or other vertical surface for supporting the same in an upright position.

Provision is likewise made for the introduction of articles to be disposed of such as cigarette or cigar ashes or butts by providing an opening 43 in the uppermost portion of the receptacle, about which a guard or other confining means 41 is placed to direct articles to be disposed of within said opening. An inwardly depending match striking plate 42 may be positioned within said opening, disposed from one side wall to the other and a grill 43 having open work 44 may be similarly placed on the opposite side wall thereof, nearest the receptacle supporting surface. A slot 45 formed by the inwardly depending edges of said match striking plate 42 and the grill 43, is provided for receiving live cigarette or cigar butts, while the open work 44 of the grill 43 is adapted to receive such butts when extinguished thereon.

The front surface of the receptacle 37, is provided with an enlarged opening 46, in which a slideable door 47 is adapted to be raised and lowered, said door having a depression 48 near its top and in line with its center, to provide access for the fingers of the user enabling the opening of the door by lifting the same vertically.

Means is also provided to dust-proof the opening 46 and to provide guiding and locking means for said slideable door by mounting the backplate 49 above and behind the slideable door 47. The plate 49 is provided with angularly disposed flanges 50 through which rivets or other fastening elements 51 are adapted to secure the same to the side walls of the receptacle 37. An additional flange 52, disposed along the uppermost edge of said plate and transversely of the flanges 50, is similarly secured to the front wall of the receptacle 37 by means of rivets or other suitable fastening elements 53. The said plate positioned and secured as described above will thereby serve as an inner guiding means for the door 47, and as a dust proofing element since it forms a seal about said door.

The aforementioned plate 49 is provided with

a shoulder 54 at the point where the flange 52 is bent inwardly for contact with the forward surface of the receptacle 37, said shoulder not only serving to dust proof the opening, as previously described, but also a limit stop for the door 47, thereby preventing the same from being raised too high, in which event the hand depression 48 will be covered.

A tumbler lock 55 may be mounted on center in the door 47, directly beneath the hand depression 48. Said lock preferably is of the removable type so that it may be inserted only when the door is in its lowermost and sealing position, as shown in Fig. 5. When the door is raised, however slightly, the barrel of the lock 55 extending inwardly will not clear the opening in which it is contained in the door by reason of the plate 49 obstructing the same. It should therefore be noted that the door 47 may be locked only when in its lowermost and sealing position, thereby providing a dust proof structure.

The barrel of the lock 55 extended inwardly from the door 47 when in this position will engage the lowermost extremity of the plate 49, preventing the opening of the door, except by those having a key, thereby keeping children and other curious people from disturbing the contents therein.

The cut-out portion 46, providing the opening in which the door 47 is contained, does not extend entirely to the side walls of the receptacle 37, but shortly therefrom, forming ears or flanges 56, which flanges provide the outer guides for the door 47.

A curved deflector plate 57 is also provided within the receptacle 37, and is secured thereto by means of rivets or other fastening elements 58, at a point opposite from that of the opening 46 and serves as a guiding means for directing articles to be disposed of, such as cigarette or cigar ashes or butts to a removable receiving tray 59 located at the bottom of the receptacle 37. Said receiving tray may contain sand, or chemical for extinguishing ignited butts which may be dropped therein and for discouraging any offensive or obnoxious odors arising therefrom. It should be noted that by reason of the sealing means of the door 47, circulation of air through the receptacle is negligible as the only open part

of said receptacle is at the top where the grill 43 and the match striking plate 42 are located.

It will be obvious to those skilled in the art that various changes may be made in the invention without departing from the spirit and scope thereof and therefore the invention is not limited by that which is shown in the drawing and described in the specification but only as indicated in the appended claim.

10. What is claimed is:

Disposal means comprising an open top receptacle having sides and end walls, an upwardly and outwardly projecting narrow guard secured to the top of said receptacle along one side and both end walls of the receptacle for directing disposable material into the same, a grill projecting inwardly from the top of the other side wall of the receptacle and terminating in downwardly directed portion spaced from the said one side wall, said grill having slots extending from said one side wall toward said downwardly directed portion, said grill having a continuous bar portion at its terminus extending between and filling the space between said end walls, an inwardly and downwardly projecting lip extending from the said one side wall toward the bar portion of the grill and terminating a distance from the latter an amount substantially greater than the width of said slots to permit the disposal of larger material.

LOUISE E. HARRIS.
